UNITED STATES PATENT OFFICE

JACOB S. SHERMAN, OF CHICAGO, ILLINOIS, ASSIGNOR TO UNIVERSAL LAMP CO., OF CHICAGO, ILLINOIS, A CORPORATION OF ILLINOIS

DESIGN FOR A TOBACCO HUMIDOR

Application filed June 30, 1930. Serial No. 36,229. Term of patent 14 years.

To all whom it may concern:

Be it known that I, JACOB S. SHERMAN, a citizen of the United States, residing at Chicago, in the county of Cook and State of Illinois, have invented a new, original, and ornamental Design for a Tobacco Humidor, of which the following is a specification, reference being had to the accompanying drawing, wherein

The figure is an elevational view of a tobacco humidor embodying my design.

I claim:

The ornamental design for a tobacco humidor substantially as shown.

JACOB S. SHERMAN.
